UNITED STATES PATENT OFFICE.

GUY S. MEWHIRTER, OF HULETT, WYOMING.

CASKET-LOWERING DEVICE.

1,070,508.

Specification of Letters Patent. Patented Aug. 19, 1913.

Application filed June 27, 1910. Serial No. 569,181.

To all whom it may concern:

Be it known that I, GUY S. MEWHIRTER, a citizen of the United States, residing at Hulett, in the county of Crook, State of Wyoming, have invented certain new and useful Improvements in Casket-Lowering Devices; and I do hereby declare the following to be a full, clear, and exact description of the invention, such as will enable others skilled in the art to which it appertains to make and use the same.

The invention relates to a coffin attachment and more particularly to the class of casket lowering devices.

The primary object of the invention is the provision of a device of this character in which a casket may be conveniently lowered into a grave and that will permit the concealment of the said lowering medium after the casket has been lowered into the bottom of the grave.

Another object of the invention is the provision of an attachment for caskets or other receptacles, which when disposed at or secured to the same at suitable points, will facilitate the lowering of the same without the use of hand straps, the device including a spring drum having a tape normally wound thereon and adapted to unwind by the weight of the casket, while such tapes are provided with hand grips and means for relieving the spring drum of the weight of the casket when the tape is unwound.

With these and other objects in view the invention consists in the construction, combination and arrangement of parts as will be hereinafter more fully described, illustrated in the accompanying drawings disclosing the preferred form of embodiment of the invention and pointed out in the claims hereunto appended.

In the drawings:—Figure 1 is a top plan view of a coffin with the lowering mechanism mounted thereon. Fig. 2 is a vertical transverse sectional view through one of the devices. Fig. 3 is a vertical longitudinal sectional view thereof. Fig. 4 is a side elevation of a coffin with the invention applied thereto. Fig. 5 is a fragmentary plan view of a portion of one of the straps near its inner end with the stop thereon. Fig. 6 is an edge view thereof.

Similar reference characters indicate corresponding parts throughout the several views in the drawings.

Referring to the drawings by numerals 5

designates a coffin which is of the ordinary well-known construction the same being shown merely to illustrate the manner of mounting the invention thereon and the operation thereof as will be hereinafter more fully described. To the side walls of the coffin 5 near opposite ends thereof are connected the lowering devices each comprising a hollow casing 6 in which is centrally located a stud spindle 7 the latter being bifurcated as at 8 for a portion of its length and within this bifurcation is engaged one end of a coiled winding spring 9 the latter being disposed within a rotatable drum 10 the same being provided with suitable central openings through which is passed the spindle 7 which latter forms a journal for the said drum 10 during its rotation within the casing 6 of the device, the spring 9 having its other end fixed to the inner face of the periphery of the drum 10 so that upon rotation of the said drum in one direction the spring will be wound upon the spindle 7 for a purpose as will be hereinafter more fully described. Fixed to the periphery of the drum 10 of each device is one end of a strip of web 11 the latter being normally wound exteriorly upon the drum and this web has its opposite free end slidably protruded through a slot 12 contained in the upper face or top of the casing 6, the free end of the web being connected with a loop handle 13 so that a person may manually grip the protruded end of the web 11 when it is desired to automatically lower the coffin 5 within a grave to the bottom thereof.

Each case 6 has a suitable opening in its outer side face which is normally closed by a closure plate 14 the latter being detachably secured by suitable fasteners 15 so that upon removing the same the plate may be detached to permit access to be had to the interior of the casing 6. On each web 11 near the end connected to the drum 10 is fixed a stop member 16 the latter adapted to engage the inner face of the chamber 17 in which the drum is mounted circumferentially of the opening 12 in the top of the said casing on the unwinding of the said web 11 to relieve the strain of the weight of the coffin 5 upon the spring 9 within the drum when the said coffin has been lowered within the grave.

In the operation of lowering the coffin 5 it is necessary for four attendants to engage the hand loops 13 on the free ends of

the webs 11 normally wound upon the drums 10 within the casing 6 whereupon the weight of the coffin 5 will cause the unwinding of the said webs 11 from the drums 10 causing 5 the springs 9 to be wound upon the spindles 7 and on the complete unwinding of the webs from the drums 10 the stop members 16 will engage the inner faces of the tops of the chamber 17 circumferentially of the 10 openings 12 thereby relieving the weight of the coffin 5 from the said springs 9 after it has been lowered within the grave to the desired distance. After the coffin has been lowered in the grave the attendants release 15 the free ends of the webs 11 whereupon the spring 9 will cause the automatic winding of the webs 11 upon the drums 10 so that the said webs will become concealed within the casing 6 of the device.

20 What is claimed is:—

1. An attachment for caskets comprising a casing having a drum rotatably supported therein, a webbing normally wound upon said drum, a spring adapted to be wound on 25 the unwinding of the webbing from the drum and effecting the rewinding of the

webbing upon the drum when said webbing has been released and means to relieve the strain of the casket upon the spring when said webbing has been unwound.

30

2. The combination with a casing having a chamber therein and a slot through the casing communicating with the chamber; of a shaft centrally mounted within the casing, a drum rotatable on the shaft, a spring 35 connecting the shaft and drum, a webbing connected to the periphery of the drum and extending through the slot, said spring normally winding the webbing on the drum, a handle carried by the webbing at its free 40 end and a fixed stop member carried by the webbing near its end connected to the drum to engage the inner face of the casing and remove strain of the weight of an object supported upon the webbing from the 45 spring.

In testimony whereof, I affix my signature, in presence of two witnesses.

GUY S. MEWHIRTER.
